(57) **CLAIM**

The ornamental design for a laundry cup caddy, as shown and described.

DESCRIPTION

FIG. 1 is a perspective view of the laundry cup caddy showing the claimed design;

FIG. 2 is a side elevation view of the laundry cup caddy mounted on a shelf with a laundry dispenser and liquid measuring cup in place. The other side is identical;

FIG. 3 is a front elevation view of the laundry cup caddy mounted on a shelf with a laundry dispenser and liquid measuring cup in place;

FIG. 4 is a top elevation view laundry cup caddy; and,

FIG. 5 is a bottom elevation view of the laundry cup caddy. The broken line showing of a shelf and laundry dispenser in FIGS. 2 and 3 is included for the purpose of showing environmental portions of the laundry cup caddy and forms no part of the claimed design.
